**ROTARY SELECTOR SWITCH CONSTRUCTION
WITH ROTOR INTERLOCKING MEANS**
Edward J. Mastney, Hinsdale, Ill., assignor to Oak Manufacturing Co., a corporation of Delaware
Filed July 2, 1962, Ser. No. 206,862
21 Claims. (Cl. 200—6)

This invention relates to an electrical switch, and, more particularly, to a rotating miniature switch adapted to be assembled in multiple sections.

It is an object of this invention to provide an improved switch.

It is a further object of this invention to provide a switch of a construction which is readily sealed against effects of changing atmospheric conditions such as humidity.

It is still a further object of this invention to provide a low-cost switch that is readily assembled into a plurality of ganged sections for switching externally connected electrical circuits.

Accordingly, it is one feature of this invention to provide a rotary switch comprising a housing, a body portion, including a stator having electrical contacts, held in the housing, a rotatable member having a contact arm extending through the housing into body portion, and means in said rotatable member for positioning the body portion with respect to the rotatable member in a fixed spatial relationship wherein the contact arm is held in rotatable contact with the electrical contacts.

It is a further feature of this invention to provide a switch wherein there is provided a rotor, a driving shaft, and a stator held in fixed spatial relationship with said rotor and wherein is provided a slidable coupling between the rotor and the shaft to provide proper seating of a contact arm held by the rotor with the stator.

It is yet a further feature of the invention to provide a rotor having a plurality of projections having an annular groove formed thereabout for engaging with a stator, which flex inwardly to allow seating of the rotor in the annular recess.

Still another feature of the invention is to provide a multiple section switch having a shaft, a plurality of rotors couplable to each other in a series relationship, one of said rotors couplable to the shaft and a plurality of stators individually held in individual recesses in the rotors wherein the coupling between shaft and stator allows for slidable longitudinal motion to provide proper contact between individual contact arms held in said rotors with respective stators.

Further features and advantages of the invention will become apparent from the description of the following drawings, wherein like parts have like reference numerals and wherein:

FIGURE 1 is a perspective view of the switch embodying the invention;

FIGURE 2 is a switch similar to FIGURE 1 with portions of the cover broken away;

FIGURE 3 is a sectional view along lines 3—3 of FIGURE 2;

FIGURE 4 is a sectional view along lines 4—4 of FIGURE 3;

FIGURE 5 is a sectional view along lines 5—5 in FIGURE 3;

FIGURE 6 is a sectional view along lines 6—6 of FIGURE 2;

FIGURE 7 is a sectional view along lines 7—7 in FIGURE 2;

FIGURE 8 is a sectional view along lines 8—8 in FIGURE 3;

FIGURE 9 is a sectional view along lines 9—9 in FIGURE 3;

2

FIGURE 10 is a sectional view along lines 10—10 in FIGURE 3;

FIGURES 11 and 12 together comprise an exploded view of the switch;

FIGURES 13 through 17 are alternate views of the reverse sides of individual items shown in FIGURES 11 and 12; and

FIGURE 18 is a sectional view of a second embodiment of the invention.

10 Referring now to FIGURES 11 through 17, which show an exploded view of the switch and include detailed views of the elements thereof, the switch may best be understood by dividing it into three portions, the housing, the shaft and rotor, and the stator portion.

15 The housing includes a bushing 20, a front cover 21 and a rear cover 22. The bushing, generally cylindrical in shape, includes a threaded portion 23 and a portion of enlarged diameter 24, including a pair of keyways 25, 26 and an annular section 27 having an outer portion 20 slightly larger than the shank portion. A cylindrical aperture 28, generally coaxial with the bushing 20, receives a shaft through the bushing. In addition, there is a stop pin 29 having its axis generally parallel to the axis of the cylindrical aperture and extending into the 25 housing when the bushing 20 is mounted on the front cover 21.

The front cover 21 is generally square in cross section and has a circular aperture 31 slightly smaller than the outer rim of the annular portion 27 which receives aperture 31 and holds it in a sealed relationship.

30 In addition, a pair of keys 32, 33 are adapted to engage the keyways 25 and 26 on the bushing. The end of the front cover opposite the aperture 31 is formed with a tapered portion 34. The rear cover 22 has a tapered 35 recess 35 corresponding in configuration to the tapered portion 34 of the front cover which it receives in a sealed relationship. The rear cover has a rectangular cross section similar to that of the front cover, and when the switch is assembled, the entire housing is substantially 40 sealed against varying air and humidity conditions. The rear cover also includes a plurality of wire-receiving nipples 36 and allows a plurality of wires 37 to pass therethrough for connecting to electrical circuits to be switched. The length of the rear cover 22 varies depending upon the number of switch sections to be incorporated in the switch, and FIGURE 18 shows a switch including three such sections.

45 The rotating portion of the switch includes a shaft 40, clamping ring 41, rotor 42, a contact spring 43, and a 50 rotor plug 44. In the embodiment of the invention shown in FIGURE 18, a plurality of rotor members and contact springs are shown. Such structure will be discussed hereinafter.

55 Shaft 40, in this instance composed of stainless steel, has an annular recess 45 formed therein for receiving clamping ring 41 when shaft 40 is in place in the cylindrical aperture 28 of bushing 20. This serves to maintain the shaft against a longitudinal motion but allows it to be rotated about its axis. A portion 46 of the shaft 60 40, having a larger diameter than the rest of the shaft, has a recess 47 formed therein for engaging with stop pin 29 under certain operating conditions to be hereinafter discussed. In addition, portion 46 has a cylindrical aperture 48 formed therethrough for receiving an index spring 49 and a pair of index balls 50, 51. A series of projections 52 extending longitudinally from the portion 46 define a pair of mutually perpendicular slots 53, 54 whose axes intersect with the axis of the shaft.

65 Rotor 42, of an insulating material, has a pair of ridges 60, 61 formed on one face of the rotor mutually perpendicular and extending longitudinally from the rotor 70 75 80 85 90 95

42. On the face of the rotor opposite ridges 60, 61 are a plurality of tapered projections 63 extending longitudinally from the rotor and defining a pair of mutually perpendicular slots 64, 65 which extend into the rotor 42 and provide for receiving the contact spring 43. In addition, a slot 66 extending circumferentially around the tapered projections 63 is provided for maintaining pressure on the contact spring as hereinafter discussed. Ridge 60 having a flaring end portion has a width dimension slightly larger than the slot width 53 on shaft 40 and provides a frictional fit therewith when the rotor and shaft are assembled and allows some longitudinal motion of the rotor.

Rotor plug 44 has a pair of longitudinally extending mutually perpendicular ridges 70, 71 and is adapted to be inserted in the slots 64, 65 of the rotor. Ridge 70 has a tapered end portion slightly larger than the slot width 65 in rotor 42 and provides slidable frictional coupling when the rotor plug is assembled in the rotor.

A sealing ring 72 provides a seal between shaft 40 and front cover 21 when the shaft is assembled in the bushing 20 and provides for sealing the entire housing.

The inner stationary portion of the switch includes an index plate 80, a front spacer 81, a stator 82, and a rear spacer 83. FIGURE 15 shows the stator 82 to include a plurality of arcuate electrical contacts 85 formed about an aperture 86. A series of tabs 87 extend from the contacts and provide connections to a plurality of wires 37. The arcuately arranged contacts are selected so that certain switching functions may be performed in electrical circuits connected to the wires 37. The arrangement is determined by the specific switching functions desired. When assembled, stator 82 fits into the annular recess 66 on rotor 42 providing contact pressure between contact spring 43 and the arcuate electrical contacts 85. The tapered longitudinally extending members 63 provide for such assembly compressing as the stator is pushed towards the rotor and spring back after the annular aperture 86 is positioned within the slot 66.

Rear spacer 83 has a series of slots 90 extending longitudinally about its periphery that allow wires 37 therethrough and permits the wires to pass through nipples 36.

Front spacer 81 is provided to properly position index plate 80 with respect to the portion 46 of shaft 40.

Plate 80 of stainless steel has an aperture formed therein having a plurality of index recesses 91 and a plurality of substantially planar faces 92.

The index plate 80, front and rear spacers 81, 83 and stator 82 are held in fixed relationship by a spring washer 94 and a pair of spring wires 95, 96. Slots in the front and rear spacer, stator, and index plate are provided for the wires.

When the shaft is rotated, the balls 50, 51 are moved from one detent recess 91 along a planar surface 92 to the next recess 91. At the same time, the contact spring is rotated by the rotor 42 and contact is made between different arcuate electrical contacts on the stator 82. Thus, the switching of external circuits is performed.

FIGURE 1 is a view of an assembled switch constructed in accordance with the invention and includes bushing 20, front cover 21 and rear cover 22. The dashed line portion 101 represents possible extensions of the switch when multiple section switches are desired. FIGURE 2 is a view similar to FIGURE 1 with a portion of the front and rear covers broken away and shows a single switch section in assembled position.

FIGURE 3, a partial sectional view along lines 3-3 of FIGURE 2, shows the assembly of a single section switch. In this view, the shaft is in substantially the same position as shown in the exploded views of FIGURES 11 and 12. Contact arm 43 is shown contacting arcuate contacts on stator 52 completing the electrical circuits between a pair of wires 37.

FIGURE 4, a sectional view along lines 4-4 of FIGURE 3, shows balls 50, 51 under the urging of index spring

49 engaging detent or index portions 91 of the index plate 80 and the dashed lines show a second position of the shaft and balls.

FIGURE 5, a detailed sectional view along lines 5-5 of FIGURE 3, shows a portion of contact spring member 43 contacting arcuate contact sections 85 and completing the electrical circuit between a pair of wires 37. The dashed lines show a second position of the contact spring member 43 when the shaft has been rotated to a second position.

FIGURE 6 is a partial cross-sectional view along lines 6-6 in FIGURE 2 with the shaft in the position indicated in the exploded view of FIGURES 11 and 12. Pin 29 is shown in the recess section 47 of shaft 40. Ridge member 60 is shown in the slot defined by projections 52 of the rotor and is in slidable mechanical contact therewith. The locking arrangement between the tapered projection 63 of rotor 42 and the ridge section 70 of rotor plug 44 is illustrated. Stator 82 is shown confined within the recess portions 66 of rotor 42.

FIGURE 7, a partial cross-sectional view along lines 7-7 of FIGURE 2, wherein the shaft is partially rotated from the position shown in FIGURES 11 and 12, further illustrates the mating between the shaft, rotor, and rotor plug.

FIGURE 8, a sectional view along lines 8-8 in FIGURE 3, illustrates the relationship between pin 29 and the recess portion 47 on shaft 40. In this view, the shaft has been rotated 60° from the position shown in FIGURES 11 and 12.

FIGURE 9, a sectional view along lines 9-9 in FIGURE 3, shows the spring washer 94 in position and held therein by the wires 95, 96.

FIGURE 10, a sectional view along lines 10-10 in FIGURE 2, shows the wires 95, 96 in position to hold the index number, front spacer, stator, and rear spacer in a fixed relationship. In this figure, the shaft 40 has been rotated 45° from the position shown in FIGURE 3.

FIGURE 18 is a partial cross-sectional view of a switch having three switch sections ganged for operation from a common shaft. In this figure, parts similar to parts discussed in the previous figure carry similar reference numerals. The multiple section switch is shown mounted through an aperture in a wall 110 and held in place by a bolt 111. A modified rear cover 112 is shown having tapered recess 113 for receiving the tapered portion 34 of front cover 21. The rear cover has sufficient length to enclose within the housing a multiple switch section. Such length is determined by the number of sections to be ganged.

The rotating portion of the switch includes shaft 40 driving a plurality of rotors 42 and having a rotor plug 44. As previously discussed, the ridge members 60, 61 provide the direct coupling between rotors and between the first rotor and the longitudinal projections 52 on shaft 40.

An index plate 80 and a front spacer 81 are provided as before, and, in addition, there are two additional spacers 114 and 115 and a rear spacer 83. A spring washer 94 similar to the previous spring washer is held against the rear spacer 83 by a wire 116 of sufficient length to extend through recesses in the spacers and to clamp the index plate 80 and the spacers in a fixed physical position with respect to each other. A second wire similar to wire 116 is provided (but not shown). As before, individual stators 82 are confined within recesses in respective rotors and electrical contact is maintained between the arcuate contacts on the stators and the contact arms. Wire 120 is shown electrically connected to an arcuate contact on the leftward stator, wire 121 connected to the middle stator and wire 122 connected to the rightwardly positioned stator. Additional wires 123 and 124 are shown extending from the rear cover but are not shown connected to any of the stators for the sake of clarity, it being understood that they would make electrical contact within the switch.

65

70

75

Assembly of the switch as shown in the first seventeen figures is as follows. Bushing 20 is mounted to front cover 21 and pin 29 is inserted in the bushing. A rotor is then inserted in the slots 52 on shaft 40, a contact spring placed in the slots 64, 65 of the rotor and the stator, having wires soldered to respective ones of the arcuate contacts, is forced over the tapered members of rotor 42 and seats itself in the recess 66 of the rotor. Then, rotor plug 44 has its projections 70, 71 fitted into the respective slots on rotor 42 with which it locks. The rear spacer and the spring washer, having wires 95, 96, are then placed adjacent the stator, and the entire shaft and spacer assembly is placed in the rear cover with the wires from the stator extending to nipples 36. A front spacer 81 is then placed adjacent the stator and the index plate assembled next to the front spacer with the wires 95, 96 then clamped into position. Index spring 49 and balls 50 and 51 are placed in the cylindrical aperture 48 prior to the assembly of the index plate. A sealing ring is placed upon shaft 40 and the entire assembly fitted together with the front cover and bushing and held in place by clamping ring 41.

FIGURE 3, among others, clearly illustrates the sliding frictional coupling between the shaft 40 and rotor 42. As can be seen in this figure, shaft 40 is fixedly held against longitudinal motion in the bushing 20 by clamping ring 41 and the sealing ring 72 butting against the shaft. In a like manner, the index plate 80, front spacer 81, stator 82, and rear space 83 are coupled in fixed relationship by the spring washer 94 and wires 95, 96. The wires 37, extending through nipples 36 and making contact with arcuate contacts on stator 82, are in a like manner fixedly held within the nipples. Therefore, the rotor 42 positions itself with respect to stator 82, and the projections 60, 61 on rotor 42 slide with respect to the projections 52 on shaft 40 to allow for this seating.

In a like manner, as shown in FIGURE 18, wherein a plurality of rotors and stators are coupled and driven by a shaft 40, sliding motion along the longitudinal axis of the switch is provided by the respective projections on 40

In one embodiment of the switch, the actual dimensions of some of the component parts are as follows:

Shaft 40—Length 1.564", diameter of portion 46, .240" Rotor 42—Axial length .212", depth of slot 64, 65, .134", 45 major diameter of projection 63, .171", diameter of slot 66, .150"

Stator 82—Width and height .350", aperture 46 diameter .156"

Index plate 80—Front spacer 81, rear spacer 83, width 50 and height .350"

Front cover 34—Outer dimension .400" sq., inner dimension .356" sq., length .200"

Rear cover 22—Outer dimension .400" sq., inner dimension .356" sq., length .261

Bushing 20—Overall length .368

I claim:

1. A rotary switch comprising: a housing; a body portion, including a stator having electrical contacts, held in said housing; a rotatable member, having a contact arm, extending through said housing into said body portion; means associated with said rotatable member for positioning said body portion with respect to said rotatable member in a fixed spatial relationship wherein said contact arm is held in rotatable contact with said electrical contacts; a shaft extending into said housing; and means coupling said rotatable member to said shaft for rotation therewith and for limited longitudinal movement with respect thereto.

2. A rotary switch comprising: a housing; a body portion, including a stator having electrical contacts and an index plate, held in said housing; a rotatable member, having a contact arm and indexing means, extending through said housing into said body portion; means asso-

ciated with said rotatable member for positioning said body portion with respect to said rotatable member in a fixed spatial relationship wherein said contact arm is held in rotatable contact with said electrical contacts and wherein said indexing means is confined within said index plate; a shaft extending into said housing; and means coupling said rotatable member to said shaft for rotation therewith and for limited longitudinal movement with respect thereto.

3. A rotary switch comprising: a housing including a stop means; a body portion, including a stator having electrical contacts, held in said housing; a rotatable member, having a contact arm and a recess operably associated with said stop means, extending through said housing into said body portion; means associated with said rotatable member for positioning said body portion with respect to said rotatable member in a fixed spatial relationship wherein said contact arm is held in rotatable contact with said electrical contact; a shaft extending into said housing; and means coupling said rotatable member to said shaft for rotation therewith and for limited longitudinal movement with respect thereto.

4. A rotary switch comprising: a housing; a body portion, including an index plate, a front spacer, a stator having electrical contacts and a rear spacer confined in that order within said housing; means for holding said plate, front spacer, stator, and rear spacer in a fixed relationship; a rotatable member, having a contact arm and indexing means extending through said housing into said body portion; and means associated with said rotatable member for positioning said body portion with respect to said rotatable member in a fixed spatial relationship wherein said contact arm is held in rotatable contact with said electrical contacts and wherein said index means is operably associated with said index plate.

5. The rotary switch of claim 4 wherein said index means includes a pair of balls held in an aperture within said rotatable member and urged against the index plate by an index spring.

6. A rotary switch comprising: a housing having a front cover and a rear cover joined in sealed relationship, said front cover having an aperture formed therein; a bushing in sealed relationship in said aperture and having a stop member extending into said housing; a shaft extending through said bushing and having a portion thereof operably associated with said stop member for limiting the rotation thereof; a rotor, having a contact arm; means coupling said rotor to said shaft for rotation therewith and for limited longitudinal movement with respect thereto; a body portion, including a stator having electrical contacts, held in said housing; and means associated with said rotor for positioning said body portion with respect to said rotor in a fixed spatial relationship wherein said contact arm is held in rotatable contact with said electrical contacts.

7. The rotary switch of claim 6 wherein a seal ring is mounted on said shaft for sealing said switch.

8. The rotary switch of claim 6 wherein a plurality of wires are electrically connected to said electrical contacts and extend through said rear cover.

9. The rotary switch of claim 6 wherein a rotor plug is fixedly engaged with said rotor for maintaining said fixed spatial relationship.

10. In a rotor for a rotary switch, a cylindrical body portion having first and second end faces and having a longitudinal axis; a pair of intersecting ridges formed on said first face for coupling to a driving shaft; a conically shaped extension formed on said second face; a pair of intersecting slots extending through said conical portion into said body portion; and a groove formed about said conical section for engaging with a stator.

11. The rotor of claim 10 including a rotor plug adapted to be inserted into said pair of slots for maintaining a stator in said groove.

12. The rotor of claim 11 wherein locking projections

are provided in said intersecting slots and said rotor plug for maintaining said plug in a fixed position with respect to said rotor.

13. The rotor of claim 10 wherein a contact spring is maintained in said intersecting slots.

14. A rotary switch comprising: a rotor having a longitudinal axis and first and second ends; a contact arm; means formed in said first end for containing said arm and for holding said arm at a substantially fixed longitudinal position on said rotor rotating means; means formed in said second end for coupling said rotor to a rotating means; said stator having a central aperture and arcuately arranged electrical contacts; and means formed on said first end for positioning said rotor with respect to said aperture so that said arm contacts said electrical contacts.

15. A multiple section rotary switch comprising: a plurality of rotors, having individual contact arms, arranged along a longitudinal axis wherein adjacent rotors are coupled together; a plurality of stators, individually having central apertures, each stator having at least one stator contact; means confining each individual rotor within the aperture of one of said stators; means loosely connecting said rotors for automatically adjusting the coupling between adjacent rotors to maintain said arms in contact with said stator contacts; and means adjustably coupled to one of said rotors for rotating all of said rotors.

16. A rotary switch comprising: a stator having spaced contacts; a rotor rotatably mounted in said stator and having a recess; a contact mounted in said rotor recess for rotation with said rotor and for movement into and out of engagement with said stator contacts; and means on said rotor for axially retaining said stator, whereby said stator holds said rotor contact in said rotor recess.

17. A rotary switch comprising: a plurality of abutting switch sections collectively defining a multiple section switch; at least one tie rod extending longitudinally along said switch sections and having a bent end portion embracing the outer switch section at one end of said switch; and spring means integral with the other end of said tie rod and engaging the outer switch section at the other end of said switch to urge said switch sections toward each other.

18. A rotary switch comprising: a housing including a front housing member having an open front end; a stator in said housing and having a plurality of contacts; a rotor rotatably mounted relative to said stator and having at least one contact movable into and out of engagement with said stator contacts; a shaft coupled to said rotor for rotation thereof and extending outwardly of said housing open end; a bushing in said housing open end and rotatably supporting said shaft; means providing a seal between said housing and said bushing; means providing a seal between said shaft and said bushing; and a rear housing member sealingly engaging the rear end of said front housing member.

19. A rotary switch comprising: a stator having spaced contacts; a rotor rotatably mounted in said stator and carrying at least one contact; a shaft; means supporting said shaft for rotation relative to said stator; and means coupling said rotor to said shaft for rotation therewith

and for limited longitudinal movement with respect thereto.

20. A multiple section rotary switch comprising: a plurality of axially aligned rotors, each rotor having an extension at one end thereof and a recess at the other end thereof, adjacent rotors being coupled for rotation together by the interfitting of a rotor extension in an adjacent rotor recess; a rotor contact mounted in each rotor recess; a circumferential groove extending around each rotor; a stator mounted in each groove and having spaced stator contacts, each said stator being positioned in abutting relation with one of said rotor contacts, whereby upon rotation of said rotors, said rotor contacts are moved into and out of engagement with the contacts on the abutting stator to effect the switching action; and at least one longitudinally extending tie rod passing through each of said stators to lock said stators against rotation.

21. A multiple section rotary switch comprising: a plurality of axially aligned rotors, each rotor having an extension at one end thereof and a recess at the other end thereof, adjacent rotors being coupled for rotation together by the interfitting of a rotor extension in an adjacent rotor recess; a rotor contact mounted in each rotor recess; a circumferential groove extending around each rotor; a stator mounted in each groove and having spaced stator contacts, each said stator being positioned in abutting relation with one of said rotor contacts, whereby upon rotation of said rotors, said rotor contacts are moved into and out of engagement with the contacts on the abutting stator to effect the switching action; insulating spacers between adjacent stators to define with said stators a stator assembly, at least one row of aligned notches in each of said stators and said spacers; and a tie rod extending through said row of notches and having a bent end portion embracing one end of said stator assembly, and a spring clip at the other end of said tie rod and engaging the other end of said stator assembly.
